(57) **CLAIM**

We claim the ornamental design for an umbilical splint, as shown.

DESCRIPTION

FIG. 1 is a perspective view taken from the front and one side showing the design;
FIG. 2 is a top view of the design shown in FIG. 1;
FIG. 3 is a side elevational view of the design shown in FIG. 1; and,
FIG. 4 is a bottom view of the design shown in FIG. 1.
